INSULATOR BRACKET

Ronald J. Bertling, South Milwaukee, Wis., assignor to McGraw-Edison Company, a corporation of Delaware

Filed Apr. 4, 1956, Ser. No. 576,150

2 Claims. (Cl. 248—67.7)

The present invention relates to insulator brackets, or so-called secondary brackets, used in connection with supporting insulators for power and light conductors. Such devices ordinarily comprise a base member provided with supporting elements projecting therefrom, which supporting elements are designed to receive a rod or the like, upon which the insulators are mounted.

As heretofore constructed, it has been common practice in the art to provide sheet metal constructions including support arms being formed of sheet metal, and it is well known to provide racks of forged members having a substantially circular cross section intermediate the ends thereof. However, as far as can be determined, there has been little consideration to providing a structure having relatively high strength in cantilever and at the same time being relatively inexpensive to manufacture from commercially available stock.

It is therefore among the objects of the present invention to provide an improved insulator support offering the strength of forged members, and which may be manufactured economically of oval bar stock or the like, which stock is positioned relative to a base member portion in a manner which will permit optimum resistance to cantilever forces applied to the free end thereof. The use of commercially available oval stock permits simplified upsetting procedures for providing mounting means, and in addition, provides a relatively smooth surface for sagging and stringing operations.

In the drawing:

Fig. 1 is a fragmentary side elevational view of a secondary or service rack embodying my invention.

Fig. 2 is a partial sectional view on line 2—2 of Fig. 1.

Fig. 3 is a sectional view on line 3—3 of Fig. 1.

Fig. 4 is an elevational view of a support arm removed from the base member, and shown prior to positioning and riveting in place.

Fig. 5 is a cross sectional view on line 5—5 of Fig. 4.

Fig. 6 is a cross sectional view on line 6—6 of Fig. 4.

To illustrate a preferred embodiment of the present invention, an elongated base member 10 of channeled cross section is provided, as shown more specifically in Fig. 3, having side flanges 11 and 12, which permit the body portion of the base member to extend outwardly relative to the support to which it may be connected. The base member may be connected to the wall of the building or to a pole or other suitable support by means of screws, bolts, or the like, and may be provided with the apertures 13, 14 and 15 for this purpose.

The body portion of the base member is also provided with longitudinally spaced apart apertures 16 in which are received the support members for holding an insulator supporting rod.

The outwardly extending support members 20 are preferably provided from commercially available bar stock having an oval cross section (see Fig. 5). In manufacturing the device, a suitable length of bar stock having an oval cross section, is pre-cut and flattened at an end portion to provide the relatively flat surfaces 21 and

22, which portion is intended to be positioned outwardly relative to the base member 10. The flattened portion is either drilled or stamped to provide an eye 23 (see Fig. 4) for slidably receiving the headed through rod 24, as shown in Fig. 1.

It is a part of the present invention to provide the support members 20 with the eye 23 in the position shown in order to permit the axis of the through rod 24 to be substantially normal to the plane passing through the major axis of the oval cross section of the support member 20. It will be apparent that such construction provides the greatest portion of metal in the direction of resistance to cantilever forces exerted laterally relative to the assembly or the base member 10. It has been found in actual practice that the greatest stresses on the support arms are in cantilever providing a moment arm in a direction of rotation about the base member with the longitudinal axis of the base member as the axis of rotation of such moment arm.

The initial step in the fabrication of the support member 20 is the pre-forming of the lower extending member 26 to approximate its shape as shown in Fig. 4. This can be done in conventional gripper dies which are movable laterally relative to one another (not shown). The next step in fabrication is to place the oval stock within a pair of conventional gripping dies (not shown) which have a portion recessed at the top for forming the outwardly extending opposed embossments or lugs 25. The opposed embossments, together with the major axis of the oval cross section, provide a stable surface for abutting supporting engagement with the top of the base member 10. That is, although the aforesaid cantilever forces in the direction of rotation about the longitudinal axis of the base member are proportionally greater than other forces exerted on the assembly, it is not to be forgotten that relative mounting heights above ground level of these assemblies cause additional shear forces to be imposed upon a respective support member 20 in all directions about its base. Thus a substantial stable surface is a necessity for efficient strength characteristics.

To continue with the forming of the support member, after placement of the oval stock in the gripper dies (not shown) is assured, the dies are closed and a punch having a chamber of the cross section of the lower extending member 26 (see Figs. 4 and 6) is moved endwise towards the preformed member 26, "heading" the member to the final cross section of the portion 26 and simultaneously providing the embossments 25. This operation is generally known as "upset forging."

After the piece has been formed to the configuration shown in Figs. 4, 5 and 6, it is inserted in the base member 10 in the relative position shown in Figs. 1, 2 and 3 with the major axis of the oval cross section being substantially normal to the longitudinal axis of the base member. The entire assembly, with the various support members 20 being placed therein, is either positioned in a jig as assembled, or is moved in a riveting die intermittently as each riveting operation is completed. The riveting operation is relatively simple and is provided by means of a punch forming the indentation 30 (see Fig. 3) which forces metal radially outwardly to provide the riveting flange 31 in tight clamping engagement with the base member 10.

After the support members 20 have been positioned in the base member 10, the through rod 24 is positioned in the axially aligned openings 23 of each support member with the appropriate insulator spool 35 being mounted thereon. The through rod 24 is preferably headed at one end and may be held in place by means of cotter pins (not shown) to prevent axial endwise movement thereof.

It will be apparent that the manner of mounting the

support member to the base member should be considered in its broadest aspect. That is, it is within the scope of the present invention to projection weld or otherwise weld the support member to the base. And, in fact, it is conceivable that oval cross section tubing may be used for the support members (not shown), and the end of such tubing flared to provide a surface for projection or other welding, or riveting of the member in place.

It will also be apparent that, although it is economically preferred to provide oval bar stock for making the supporting members, it is conceivable that the members may be fabricated from sintered metal or may be cast to shape if so desired.

It will be obvious that the provision of the relatively flat opposed surfaces 21 and 22 is preferably, inasmuch as the surface 21 provides a relatively extended portion for laterally supporting the spool-type insulator 35, it is possible to fabricate the support members without flattening the ends if such is found to be desirable.

It will be especially apparent that the oval cross section support members provide still another advantage in their relatively broad surface. That is, when positioned as shown with the major axis substantially normal to the longitudinal axis of the base member, the smooth oval surface of the support members will provide a less abrasive resistance during sagging or stringing conductors prior to fastening to the insulators 35. That is, in actual practice, the racks are generally mounted as viewed in Fig. 1 on a pole or wall with the through pin 24 being substantially vertical. Conductors are threaded through each rack, and the support members act to temporarily support the conductor during the sagging or stringing operation, and if they are provided with too small a surface they will tend to cause the conductor to bend sharply, and otherwise abraid the conductor during movement thereof.

Another factor in using oval stock rather than stock of round cross section, is that during the flattening operation, which provides surfaces 21 and 22, a round section tends to "grow" in an endwise direction. Obviously, such growth would materially effect the strength of the arm, and would require additional means for resisting the same in order to maintain uniformity in length for axial alignment of the openings for receiving the

through pin. It has been found that flattening has no effect on the lengthwise dimension of the oval cross section stock.

From the foregoing, it will be apparent that an improved insulator bracket has been provided which takes full advantage of economical manufacture and increased strength characteristics in the choice of cross sectional configuration of the outwardly extending support members, and which members may be formed at their inner end by a simple upsetting operation to provide a substantial and stable construction for mounting.

I claim:

1. An insulator bracket comprising an elongated channeled base member formed from sheet metal and having a plurality of spaced apart apertures therein, a plurality of support arms fixedly secured to said bracket and extending outwardly therefrom, each of said arms being forged from stock of oval cross-section with the major axis of said cross-section being substantially normal to the longitudinal axis of said base member, each of said arms further being symmetrically shaped about a plane through its longitudinal axis normal to the longitudinal axis of the base member whereby when reversed 180° said insulator bracket presents substantially identical use surfaces, the inner end portion of each of said arms having integral embossment extending outwardly relative to said major axis and abutting the outer face of said base member, said arms having a portion extending within a respective aperture of said base member, and means for fixedly securing each of said arms to said base member from the back face thereof, the outer ends of said arms having aligned apertures formed therethrough for receiving an insulator rod.

2. A structure as set forth in claim 1 wherein the outer end of each of said arms is flattened on opposed sides for a distance inwardly from said outer end.
